UNITED STATES PATENT OFFICE.

JOSEPH GRIGG, OF COLONIE, NEW YORK, ASSIGNOR TO COVERT MANUFACTURING COMPANY, OF WATERVLIET, NEW YORK, A CORPORATION OF NEW YORK.

DESIGN FOR A KEEPER FOR HOOKS.

SPECIFICATION forming part of Design No. 35,656, dated February 4, 1902.

Application filed June 26, 1901. Serial No. 66,168. Term of patent 14 years.

To all whom it may concern:

Be it known that I, JOSEPH GRIGG, a citizen of the United States, residing at Colonie, in the county of Albany and State of New York, have invented and produced a new and original Design for a Keeper for Hooks; and I do hereby declare the following to be a full, clear, and exact description of the same, reference being had to the accompanying drawings, forming a part thereof.

The invention relates to a new and original design for keepers for hooks, which will hereinafter be described and which is illustrated in the accompanying drawings.

Figure 1 is a side elevation of the keeper embodying the design, and Fig. 2 is a cross-section on the line $\alpha\alpha$ of Fig. 1.

The design, as shown, comprises two flat side members A B, each having straight lower edges inclined slightly or tapered toward the rear. These two members are connected along their upper edges by the slightly-curved portion D, forming the top, extending from end to end and having at the front a slightly-

upturned portion d. The forward edges of the sides A B are inclined rearwardly and downwardly from the point d to the lower edges and slightly incurved at the center at c. A slightly-raised portion d' is located near the upper rear portion of the keeper, and apertures d² are located near the rear of the sides.

The essential feature of the design resides in the slight-tapered formation and the flat sides, having the downwardly and rearwardly forward inclined edges extending from the extreme upper forward end, as shown.

Having thus described the invention, what is claimed as new, and desired to be secured by Letters Patent, is—

The design for a keeper for hooks substantially as shown and described.

In testimony whereof I affix my signature in presence of two witnesses.

JOSEPH GRIGG.
